CLAIM

The ornamental design for a grip container, as shown and described.

DESCRIPTION

FIG. 1 is a front elevational view of a grip container embodying our new design;

FIG. 2 is a rear elevational view of the grip container of FIG. 1;

FIG. 3 is a left side elevational view of the grip container of FIG. 1, the right side elevational view being a mirror image thereof;

FIG. 4 is a top plan view of the grip container of FIG. 1; and, FIG. 5 is a bottom plan view of the grip container of FIG. 1.

The broken lines in the drawings are for illustrative purposes only and do not form part of the claimed design.
